DESIGN.

E. W. KELLER,
FLAG OR BANNER,
APPLICATION FILED DEC. 4, 1918.

53,368.

Patented May 27, 1919.

Inventor
Eugene W. Keller
By his Attorney F. Parker

UNITED STATES PATENT OFFICE.

EUGENE W. KELLER, OF NORTH BERGEN, NEW JERSEY.

DESIGN FOR A FLAG OR BANNER.

53,368.

Specification for Design.

Patented May 27, 1919.

Application filed December 4, 1918. Serial No. 265,297. Term of patent 3½ years.

To all whom it may concern:

Be it known that I, EUGENE W. KELLER, a citizen of the United States, residing at North Bergen, in the county of Hudson and State of New Jersey, have invented a new, original, and ornamental Design for Flags and Banners, of which the following is a specification, reference being had to the accompanying drawing, forming part thereof.

The figure is a plan view of a flag or banner, showing my new design.

I claim:—

The ornamental design for a flag or banner, as shown.

EUGENE W. KELLER.

Signed in the presence of—

CLARENCE S. ASHLEY,
EDYTHE C. BARKER.
